[57] CLAIM

The ornamental design for a room divider connector or similar device, substantially as shown and described.

DESCRIPTION

FIG. 1 is a perspective view of a room divider connector or similar device showing my new design;
FIG. 2 is a front elevational view thereof; and
FIG. 3 is a top plan view thereof.

The room divider connector or similar device has been broken away in the middle of FIGS. 1 and 2 of the drawing to indicate indeterminate length.
